DRAINAGE STRUCTURE

Frank J. Schwemler, Shaker Heights, Ohio

Application August 4, 1931, Serial No. 555,081

3 Claims. (Cl. 182—6)

This invention relates to a throat for use in connection with catch basins and catch basin headers of the type commonly installed in the tree lawn and in which the header inlet opening is located in the face of the curb and extends upwardly from the pavement level, and particularly to a throat for this purpose which is exposed to water flow along the curb or across the pavement surface and which is operable to baffle the water and to collect and to discharge it into the catch basin. 5

The principal object of the present invention is to provide a throat which is supplementary to the catch basin header and may readily be installed 15 in the pavement adjacent the curb in complementary relation to headers which have previously been installed.

Another object is to provide a receiving throat of this character which may be installed in such 20 connection with only very slight changes in the portion of the pavement adjacent the header and without interfering with any subterranean conduits, tunnels, etc. often existing in or beneath pavements.

25 Another object is to effect reception and diversion of water from the pavement and to discharge the same expeditiously into the catch basin and to accomplish this result by a rigid weight supporting throat structure which is neat in appearance, simple in construction and economical to manufacture.

In most cities and counties, certain limitations are imposed in regard to catch basins and headers therefor, particularly in case of pavements having 30 a curb and in which the catch basin header is disposed in the tree lawn with an upright forward face and opening lying in the plane of the curb. In many instances, the specifications limit the height of the curb, and correspondingly the 35 header, as well as the pavement level adjacent the header opening. Consequently, the inlet opening of the header is of such small size that in case of ordinary rainfall it will not admit water in sufficient quantity and flooding of the 40 adjacent pavement results. Furthermore, due to the relative smallness of the opening and the resultant accumulation of pools of water on the pavement surface, sticks, leaves and foreign matter which would ordinarily pass into the 45 header opening with the flowing water, accumulate in the pool and the accumulated mass as a whole reaches the opening of the header and additionally blocks the same.

50 On the other hand, if this water can be disposed of quickly and without accumulating in pools, any such foreign matter will pass into the header opening as quickly as transported thereto and in small quantities and the opening is generally large enough to receive the same under such 55 conditions.

An important advantage of the present invention is the provision of a supplemental throat for assisting in breaking the flow of water across the pavement or along the curb past the header opening and discharging the same promptly and expeditiously into the catch basin so as to eliminate any accumulation on the pavement. The manner in which the throat of the present invention effects this result will become apparent from the following specification and drawings, wherein 10

Fig. 1 is a plan view of a throat embodying the principles of the present invention shown in connection with companion catch basin headers;

Fig. 2 is a plan view illustrating the use of the throat in connection with a single catch basin 15 header;

Fig. 3 is a plan view of a slightly modified throat installed in connection with a single catch basin header;

Fig. 4 is a cross sectional view taken on a plane 20 indicated by the line 4—4 of Fig. 2, showing the throat, header and a part of the catch basin associated therewith;

Fig. 5 is a sectional view taken on a plane indicated by the line 5—5 of Fig. 1; 25

Fig. 6 is a rear elevation of the throat illustrated in Fig. 3;

Fig. 7 is a sectional view taken on a plane indicated by the line 7—7 of Fig. 1, and showing a 30 part of the pavement and forward wall of the catch basin.

Referring particularly to Figs. 1, 5 and 7, the throat is shown, for purposes of illustration, in connection with companion headers 1 and 2 which surmount companion catch basins 3 and 4 respectively, the catch basins 3 and 4 having their front walls 5 disposed substantially in or slightly beyond the curb line of the pavement. The header 1 is of the usual construction and comprises an upright shell frame 6 flanged at 35 the bottom as indicated at 7 to rest upon the walls of the catch basin. The header is provided with the usual removable cover 8 and is open along the front wall as indicated at 9 and is of such height that when mounted upon the 40 walls of the catch basin, the upper surface of the header lies substantially in the plane of the upper surface of the curb. Thus the opening 9 is limited in height by the particular curb used. 45

Since the curbs, for economy, are limited in 50 height and, since, for the same reason, the header is kept at a minimum size, the opening 9 therein is only sufficiently large to accommodate the flow of water under normal conditions of rainfall and is insufficient to accommodate the water resultant from severe rains. As a result, the throat 10 is provided for supplementing the opening 9 so that even excessive flows can be accommodated. 55

In Fig. 7 the usual construction of pavement 60 is illustrated and comprises a cement base B

which is faced with suitable brick or other facing layer F. The throat 10 comprises generally an elongated weight supporting box structure, preferably in the form of a casting, having an upper right forward wall 11, and rear wall 12 and being closed at the ends by suitable end walls 13. The box is preferably spanned across its upper face by suitable grating 14 so that any water passing thereover is baffled and directed into the interior of the box. The rear wall is also weight supporting.

The floor 15 of the box is preferably sloped from its ends toward an intermediate portion, the sloping portions being indicated at 16 in Fig. 5, and also slopes from the forward wall downwardly toward the rear wall. Consequently, any water entering through the grating is directed promptly and expeditiously toward the central portion of the box. At the central portion of 20 the box the rear wall is provided with one or more suitable openings 17 from which any water received is discharged into the basin.

The throat is mounted in the pavement directly in front of the header with which to be associated. This may be accomplished readily by suitably sloping the concrete base portion B to conform to the underside of the floor 15, and, continuing along the same plane of inclination, sloping the front wall of the catch basin as indicated at 19. It should be noted that the depth of the throat is such that when placed in operating position, the floor thereof does not extend below the normal bottom level of the base B of the pavement and hence does not interfere with existing subterranean conduits and the like.

If the box is installed at the initial construction of the basin and pavement, it may readily be dropped into place and supported and the concrete poured thereabout.

40 The opening 17 discharges into the passage 20 formed in the front wall of the catch basin and from this into the basin proper, thus providing an additional opening into the basin without enlarging the exposed opening 9. The rear wall 12 of the throat is preferably upright and vertical so as to snugly engage, in face to face relationship, the exposed front wall of the header and preferably is coextensive with the front face of the header or protrudes slightly beyond the header 45 at its ends so as to abut the curb. Thus the curb and header cooperate to brace the throat in position and the throat and header form substantially a resultant unitary structure. If desired, a depending flange 22 may be provided on the 50 front wall of the throat so as to interlock with the concrete base B and thus additionally support the throat.

The throats illustrated in Figs. 1 and 2 are the same in all respects, the header in Fig. 2 being 60 designated 1b. In Figs. 3 and 6 a slightly modified throat 10' is shown installed in front of a single catch basin header 1a, the parts thereof corresponding to those of the throats above described being designated by corresponding primed numerals.

Since the floor 15 of the throat slopes both toward the midportion and rear opening, accumulation of débris, water and ice and the like in the throat is prevented.

70 It is apparent from the foregoing description that the throat herein described is effective for

the purposes above set forth, is easily handled and installed and has a neat appearance.

Furthermore it is apparent that no sudden drop or pocket in the pavement surface with the resultant annoyance to vehicular traffic results while at the same time a steep runoff adjacent the header is provided.

Having thus described my invention,

I claim:

1. A supplemental reception throat for catch basins of the curb opening type, comprising an elongated box structure having weight supporting front and rear walls and end walls and spanned at the top by a grating, said box having a floor inclined downwardly from the front wall toward the rear wall and spaced below the grating throughout its entire surface a sufficient depth to lie between the upper and lower surfaces of a pavement with which to be associated when the upper limit of the throat is disposed substantially at the level of the adjacent pavement surface, said rear wall having an opening extending upwardly from the floor level adjacent thereto for discharging the contents of the box, the rear wall surface of the box defining the rear limit of the throat whereby it may lie in the plane of the curb of the pavement in which the box is installed and the throat is entirely exposed in the pavement and the curb adjacent the header need not be disturbed.

2. A supplemental reception throat for catch basins of the curb opening type, comprising an elongated box structure having weight supporting front and rear walls and end walls and spanned at the top by a grating, said box having a floor inclined downwardly from the front wall toward the rear wall and spaced below the grating throughout its entire surface a sufficient depth to lie between the upper and lower surfaces of a pavement with which to be associated when the upper limit of the throat is disposed substantially at the level of the adjacent pavement surface, said rear wall having an opening extending upwardly from the floor level adjacent thereto for discharging the contents of the box, the rear wall surface of the box defining the rear limit of the throat whereby it may lie in the plane of the curb of the pavement in which the box is installed and the throat is entirely exposed in the pavement and the curb adjacent the header need not be disturbed, said rear wall being of greater length than the curb face of the header whereby movement of the throat is resisted by the curb.

3. A supplemental reception throat for curb opening catch basins comprising an elongated weight supporting box having front wall and weight supporting rear wall and end walls, and spanned at the top by a grating, said box having a floor inclined downwardly from the front wall to the rear wall and from the ends toward the longitudinal midportion and spaced below the grating over its entire surface a sufficient depth to lie between the upper and lower surfaces of a pavement with which to be associated when the upper limit of the box is disposed substantially in the upper surface of the pavement, said rear wall having an opening extending upwardly from the floor for discharging the contents of the throat into the catch basin.

FRANK J. SCHWEMLER.
